Dec. 1239

Washington G. Gilroy of Philadelphia, Pa.
Letters Patent No. 1339, dated April 24, 1860.

The schedule referred to in these Letters Patent and making part of the same.

To all whom it may concern:

Be it known that I, Washington G. Gilroy, of the City of Philadelphia and State of Pennsylvania, have invented or produced a new and original design for a Paint. Vessel, and I do hereby declare that the following is a full and exact description of the same, reference being had to the annexed drawings, making a part of this specification, in which,

Figure 1. represents a view of one of the four sides of the said vessel; and
Figure 2. a transverse section, presenting the inner side of the upper
end, of the same.

Like letters indicating the same parts when in the different figures.

The object of this design is, the production of a sheet metal vessel, suitable for the purpose of "putting up" white-lead or other paints, ground in oil, which will serve as a "trade-mark." It consists of a sheet metal vessel made of rectangular form, or with parallel sides and ends - the sides being ornamented with straight line indentations arranged as parallelograms - as hereinafter described.

In the drawings A, A', A", A''' represent the four sides of the vessel, each side being parallelogramic in its boundaries, and its surface indented with the straight line angular grooves b-b, which leave the flat surfaces c-c in the same plane with each other, and both, the said grooves and flat surfaces, forming together a series of parallelogramic ornamentations, as seen in the drawings.

The two ends of the vessel consist of flat plates, of sheet metal, whose edges are bent over upon the four sides, A, respectively, so as to produce, when soldered, the lap seam f-f, f-f, around the ends of the vessel.

The upper end of the vessel is provided with a circular opening e, the edge of which is slightly depressed for receiving thereon the edge of any suitable disk of sheet metal which may be soldered fast therein after the vessel has been filled with paint.

What I claim as my invention or production, and desire to secure by letters patent is -

306

Dec. 1239

A vessel of the form described, and whose sides are ornamented with the grooves b. b. and flat surfaces, c. c. as set forth - as a new and ornamental design for a paint. vessel.

Witnesses.

Benj. Morrison,
John Gilroy.
